UNITED STATES PATENT OFFICE.

MILTON C. J. BILLINGHAM, OF KALAMAZOO, MICHIGAN.

PAPER-STOCK-TREATING MACHINE.

1,384,987.

Specification of Letters Patent. Patented July 19, 1921.

Application filed April 23, 1920. Serial No. 376,058.

To all whom it may concern:

Be it known that I, MILTON C. J. BILLINGHAM, a citizen of the United States, residing at Kalamazoo, county of Kalamazoo, State of Michigan, have invented certain new and useful Improvements in Paper-Stock-Treating Machines, of which the following is a specification.

This invention relates to improvements in paper stock treating machines.

My improved stock treating machine is especially designed by me for use in disintegrating old papers for use as paper stock and for deinking such stock.

15 The main objects of this invention are:

First, to provide an improved disintegrating or defibering machine in which the fibers are effectively separated without grinding or abrading action.

20 Second, to provide an improved disintegrating or defibering machine well adapted for use in deinking printed papers and preparing the same for paper stock which produces a superior product.

25 Third, to provide an improved stock treating machine in which all of the stock is effectively treated or acted upon.

Further objects, and objects relating to structural details will definitely appear from the detailed description to follow.

30 I accomplish the objects of my invention by the devices and means described in the following specification. The invention is clearly defined and pointed out in the claims.

35 A structure which is a preferred embodiment of my invention is clearly illustrated in the accompanying drawing forming a part of this specification, in which:

Figure I is a detail view partially in vertical central section of my improved stock treating machine or apparatus.

Fig. II is a plan view thereof.

Fig. III is a horizontal section on a line corresponding to line 3—3 of Fig. I.

40 In the drawing similar reference characters refer to similar parts throughout the several views. In the accompanying drawing, I have not attempted to show or maintain the proper relative proportion of parts as these will be greatly varied to suit the capacity and the particular condition of installation, and various parts are shown in conventional form.

45 Referring to the drawing, I provide a cylindrical tank 1 disposed vertically and provided with an internally concave bottom 2

having a discharge opening 3 and an internally curved top 4. The discharge pipe 5 is connected to the discharge opening 3, the pipe having a connection 6 for the admission of the stock to be treated and the deinking solution and branches 7 connected to the intakes of the pumps 8. One of the pumps 8 is provided with a discharge pipe 9 disposed centrally through the opening 3 of the tank to project centrally within the tank. On the upper end of the pipe 9 is a nozzle 10.

The conical deflector 11 is mounted on this pipe with its lower end 12 spaced from the bottom of the tank so that the stock may flow below the deflector to the opening 3. The second pump is provided with a discharge pipe 13 terminating in the nozzle 13' disposed vertically through the top of the tank in alignment with the nozzle 10 and in a spaced relation thereto so that the streams from the nozzles impinge centrally within the tank and at the upper end thereof. The pipe 13 is provided with a connection 14 for the admission of steam or water and a connection 15 for the discharge of the treated stock.

In the structure illustrated, an electric motor is indicated conventionally at 16.

With the parts thus arranged, the stock to be disintegrated is delivered through the nozzles in impinging streams at the upper end of the tank. As these streams impinge centrally the material is quite uniformly distributed in the tank and flows uniformly to the discharge opening, that is, it is not likely to clog or bank up within the tank or adhere to the walls thereof, the upper end of the tank being curved so that the discharge from the nozzles prevents the pieces of paper or the like from adhering thereto.

It is of importance that all of the material treated circulate for the reason that should a portion fail to circulate for a time and then become dislodged, the stock is not uniformly disintegrated and is not suitable for the purposes intended.

My improved machine is especially well adapted for the treating of stock with deinking solution as the stock is not only uniformly treated but is effectively disintegrated without any grinding action which would beat or grind the ink into the fiber and thus prevent its being entirely free.

By the aid of this apparatus, I am enabled to disintegrate fibrous material such as printed paper to substantially its original

pulp condition, that is, the fibers are not shortened or broken up as by grinding or coming in contact with a hard unyielding surface as the disintegration is effected by 5 a pulling or tearing action while the material is entirely suspended in the carrying liquid.

Having thus described my invention, what I claim as new and desire to secure by Letters Patent is:

1. In a stock treating machine, the combination of a vertically disposed cylindrical tank having an internally concave bottom with a central discharge opening therein and 15 an internally curved top, pumps having their intakes connected to said tank discharge, a discharge pipe for one of said pumps provided with a nozzle and disposed vertically in said tank and centrally through said 20 discharge opening thereof with its nozzle near the upper end of the tank, a discharge pipe for the other pump provided with a nozzle disposed vertically and centrally through the top of the tank, said nozzles being in 25 alinement and spaced so that the streams therefrom impinge, and a conical deflector mounted on the first mentioned discharge pipe and having its bottom spaced from the bottom of the tank to permit the flow of 30 stock to said tank discharge opening.

2. In a stock treating machine, the combination of a vertically disposed cylindrical tank having an internally concave bottom with a central discharge opening therein and 35 an internally curved top, pumps having their intakes connected to said tank discharge, a discharge pipe for one of said pumps provided with a nozzle and disposed vertically in said tank and centrally through 40 said discharge opening thereof with its nozzle near the upper end of the tank, and a discharge pipe for the other pump provided with a nozzle disposed vertically and centrally through the top of the tank, said nozzles being in alinement and spaced so that the streams therefrom impinge.

3. In a stock treating machine, the combination of a tank having a discharge opening in its bottom, pumps having their intakes connected to said tank discharge, a discharge pipe for one of said pumps provided with a nozzle disposed vertically in said tank, a discharge pipe for the other pump provided with a vertically disposed nozzle, 50 said nozzles being in alinement and spaced so that the streams therefrom impinge, and a conical deflector mounted on the first mentioned discharge pipe and having its bottom spaced from the bottom of the tank to permit the flow of stock to said discharge opening.

4. In a stock treating machine, the combination of a tank having a discharge opening in its bottom, pumps having their intakes connected to said tank discharge, a

discharge pipe for one of said pumps provided with a nozzle disposed vertically in said tank, and a discharge pipe for the other pump provided with a vertically disposed nozzle, said nozzles being in alinement and spaced so that the streams therefrom impinge.

5. In a stock treating machine, the combination of a cylindrical tank disposed vertically, a conical deflector disposed centrally within said tank with its lower end spaced from the bottom thereof so that the stock may flow below the deflector to a central discharge opening, a nozzle disposed at the apex of said deflector to deliver upwardly, 75 a second nozzle disposed to deliver downwardly above said first nozzle and in alinement therewith so that the streams therefrom impinge, and pumps having their intakes connected to the bottom of said tank 80 and their discharges connected to said nozzles, all coacting for the purpose specified.

6. In a stock treating machine, the combination of a vertically disposed cylindrical tank having an internally concave bottom 90 with a central discharge opening therein and an internally curved top, nozzles disposed within said tank at the upper end thereof so that the streams therefrom impinge centrally of the tank, a conical deflector disposed centrally of said tank below said nozzles and over said discharge opening, and means for circulating the stock from said discharge opening to said nozzles.

7. In a stock treating machine, the combination of a vertically disposed cylindrical tank having an internally concave bottom with a central discharge opening therein and an internally curved top, nozzles disposed within said tank at the upper end thereof so 100 that the streams therefrom impinge centrally of the tank, and means for circulating the stock from said discharge opening to said nozzles.

8. In a stock treating machine the combination of a tank having a concave bottom with a central discharge and an internally curved top, a nozzle disposed centrally within said tank near the upper end thereof to deliver upwardly therein, a second nozzle 115 disposed centrally of said tank so that the streams from said nozzles impinge centrally within the upper part of the tank, and pumps having their intakes connected to the bottom of the tank and their discharges connected to said nozzles.

9. In a stock treating machine the combination of a cylindrical tank disposed vertically and having a discharge at the bottom, nozzles disposed within said tank so that the 125 streams therefrom impinge, a conical deflector disposed below said nozzles and over said discharge opening, and means for circulating the stock from said discharge opening to said nozzles.

10. In a stock treating machine, the combination of a tank having a discharge at the bottom, nozzles disposed within said tank so that streams therefrom impinge, a conical deflector disposed below said nozzles and over said discharge opening, and means for circulating the stock from said discharge opening to said nozzles.
11. In a stock treating machine, the combination of a tank, nozzles disposed vertically in an opposed relation in the upper end of said tank so that their streams impinge,
- a discharge at the bottom of said tank, and means for circulating the stock from said discharge through said nozzles, for the purpose specified.
- In witness whereof, I have hereunto set my hand and seal in the presence of two witnesses.
